UNITED STATES PATENT OFFICE

ALEXANDER G. HATCH, OF FARMINGTON, CONNECTICUT, ASSIGNOR TO THE SESAMEE COMPANY, OF HARTFORD, CONNECTICUT, A CORPORATION OF CONNECTICUT

PERMUTATION LOCK

Application filed June 29, 1928. Serial No. 289,157.

This invention relates to an improved combination lock herein disclosed as applied to an electric switch but not intended to be limited to that particular field of usefulness.

It is an object of the invention to provide a lock having a bar which may be moved endwise to either an effective or ineffective position when in either of two different angular positions, and to associate with said bar a permutation lock mechanism by which the movements from one position to another may be controlled.

In a somewhat broader sense the bar of the above-described lock may be defined as one which may be shifted from one to the other of two positions from each of which it may be displaced by a movement other than its shifting movement to a new position in which such shifting movement is prevented, the particular character of the two movements, whether angular or rectilinear, or otherwise, being of no importance.

The bar may be specially designed to serve any desired purpose, but is herein disclosed as the movable member of an electric switch or circuit-breaker, and the permutation mechanism is so associated with the bar, when in one of its angular positions, that it may be locked in its open circuit position, whereas it may be moved freely from open circuit to closed circuit position, and vice versa, when in the other of its two angular positions. The relation of the permutation mechanism to the bar is also such that when the latter is in its last-mentioned angular position, which may be designated as its "free" position, the mechanism may prevent its return to its first-mentioned angular position, which may be designated as its "controlled" position, unless the permutation mechanism is first set.

It is a further object of the invention to provide improved means whereby the combination of the lock may be readily changed and means to prevent a change of the combination by one not informed as to the combination in accordance with which the lock may have previously been set.

It is a further object of the invention to insure the return of the combination-chang-

ing mechanism to its normal condition whenever it has been operated to effect a change of the combination.

Other important features of the invention are directed to an improvement in the form and arrangement of the permutation wheels and parts thereof which facilitate the setting and reading of the combination and simplify certain parts of the mechanism intended to prevent the picking of the lock.

In the drawings illustrating the preferred form of the invention,

Fig. 1 is a face view of the lock with the permutation wheels all set at zero.

Fig. 2 is a corresponding view of the lock with the face plate removed so as to expose the permutation mechanism.

Fig. 3 is a view of the lock, partly in side elevation and partly in cross-section, along the line 3—3 of Fig. 1, looking in the direction indicated by the arrows.

Fig. 4 is a cross-sectional view of the lock along the line 4—4 of Fig. 3, looking in the direction indicated by the arrows.

Fig. 5 is a side view of the lock looking in a direction at right angles to that of the direction of view of Fig. 3, parts being removed to reveal underlying structure and parts being shown in section.

Fig. 6 is a similar view with additional parts of the mechanism removed to reveal other underlying parts of the structure.

Fig. 7 is a cross-sectional view through the switch-controlling bar, the bar being represented in the position which it occupies when turned from its controlled position to its free position.

Fig. 8 is a view similar to Fig. 7, the switch-controlling bar being indicated in its free circuit-closing position.

Fig. 9 is a view similar to Fig. 7, the bar being indicated in its free open circuit position.

Fig. 10 is a view of the lock in cross-section along the line 10—10 of Fig. 2, looking in the direction indicated by the arrows.

Fig. 11 is a cross-sectional view, along the line 11—11, of a part of the permutation mechanism shown in Fig. 10, looking in the direction indicated by the arrows.

Fig. 12 is a cross-sectional view, along the line 12—12, of another part of the permutation mechanism shown in Fig. 10, looking in the direction indicated by the arrows.

For purposes of illustration the invention is herein disclosed as applied to a switch lock adapted to be mounted on the instrument board of a motor vehicle and used as a substitute for the ordinary key-controlled switch by which the ignition circuit may be opened and closed. It comprises a casing or mounting member including a central supporting disk 20 (Figs. 1 and 5) having secured thereto an upper framework 21 and a lower framework 22. Secured at the top of the framework 21 is an upper disk 23, which may be covered by a face plate 24 held in place by a clamping and finishing ring 25 and a backing ring 26.

Mounted for endwise and rotational movement in the casing is a bar or manipulator 27 (Figs. 3 and 5), the movements of which may be controlled by a latch 28 (Fig. 6), which may, in turn, be controlled by a permutation mechanism 29.

The bar 27 is provided at its lower end with a band of copper or other electrically conductive material 30 adapted to serve as a connector by which an electric circuit may be closed between two electric terminals 31 (Fig. 3) provided with suitable binding posts (not shown) by means of which they may be included in the electric circuit to be controlled by the switch.

The band of conducting material 30 may be mounted on a sleeve of insulating material 32 carried at the end of the bar 27, a portion of which may be exposed adjacent the connector 30 so that, on movement of the bar 27, it may be interposed between the contacts 31 and thus serve as a means of opening the circuit.

The bar 27 may under certain conditions be moved from the angular position indicated in Figs. 1, 3, 5, and 6 which will hereinafter be referred to as its "A" position, to the angular position in which it is indicated in Figs. 7, 8 and 9, which will hereinafter be referred to as its "B" position. The "A" position of the bar 27 is the position heretofore referred to as its "controlled" position, and the "B" position of the bar 27 is the position heretofore referred to as its "free" position.

When in either its angular position "A" or its angular position "B", the bar 27, unless prevented by the permutation mechanism, may be moved from an open circuit position illustrated in Figs. 3, 6 and 9 to a closed circuit position indicated in Figs. 5 and 7. As a matter of convenience the two open circuit positions will hereinafter be referred to as the "A¹" position and the "B¹" position, respectively. The two circuit-closing positions will be referred to as the "A²" position and the "B²" position, respectively.

When the bar 27 is in its "B" position it may be moved to a position intermediate its "B¹" position and its "B²" position as indicated in Fig. 8, which is also a circuit-closing position with respect to the contacts 31.

Except when the bar 27 is in its "A²" position or its "B²" position, rotation from one angular position to the other is prevented by means of a pin having projecting end portions adapted to serve as stops 33, 34 (Figs. 2 and 3) and a portion of the upper framework 21 comprising a wall 35 partly surrounding the bar 27 and extensions thereof 36, 37 so positioned as to permit the stops 33, 34 to freely share the endwise movement of the bar. The height of the curved wall 35 is such that the stops 33, 34 are moved to a position just clear of the same when the bar 27 is moved to its "A²" or "B²" position. The wall elements 36, 37 extend upwardly to the disk 23 as indicated in Fig. 3. The stop 33 is of sufficient length to extend beyond the opening in the framework above the curved wall element 35, thereby preventing rotation of the bar 27 in a clockwise direction, as indicated in Fig. 2, when the bar is in its angular position "A", but the stop 34 is somewhat shorter so as to clear the wall element 37 (Fig. 2) when the bar is in its "A²" position and permit the bar to be rotated in a counter-clockwise direction, as indicated in Fig. 2, through an angle of 180° until the stop 33 is brought into contact with the wall element 37. During this movement the stop 34 moves along the upper surface of the circular wall element 35. After the bar has been thus rotated to its "B²" position, the position in which it is indicated in Fig. 7, it may be moved endwise to its "B¹" position, as indicated in Fig. 9, through the intermediate position, in which it is indicated in Fig. 8, hereinafter referred to as its "B³" position.

During this movement of the bar 27 the stop 33 is free to move along the surface of the wall element 37 and the stop 34 is free to move along the wall element 36, but the bar may not be rotated back to its "A" position except when it has been moved to its "B²" position, as indicated in Fig. 7.

The movements of the bar 27 are directly controlled by the latch 28 (Figs. 4 to 9, inclusive). As best illustrated in Figs. 4 and 6, this latch has a slot 38 at its rear end through which passes a pin 39 fixed in the lower framework 22. The forward end of the latch passes through a slot in a partition 40 also forming a fixed part of the lower framework. Intermediate the pin-and-slot connection 38, 39 and the slotted guideway 41 in the partition 40 the latch passes through a slot in a slide-bar 42, the length of the slot having sufficient clearance to permit a slight rocking movement between the latch and the slide-bar. The ends of the slide-bar 42 are mounted in guideways 43 (Figs. 4 and 10),

which permit the slide-bar, when the permutation mechanism, hereinafter to be explained, has been set in a predetermined relation, to be moved upwardly or to the left as illustrated in Fig. 6, thus permitting the latch to be rotated to a limited extent in a counterclockwise direction as indicated by broken lines. Except when the permutation mechanism has been so set, movement-obstructing elements of said mechanism prevent any appreciable movement of the slide-bar 42 from the position in which it is indicated in Fig. 6. It will be apparent, however, that, irrespective of any movement of the slide-bar, the latch 28 may be moved rearwardly, that is, downwardly, as indicated in Fig. 6, to an extent dependent upon the length of the slot 38, the free end of the latch being permitted to move through the slot 41 in the partition 40 and the slot in the slide-bar 42.

In order that the movements of the bar 27 may be controlled by the latch 28 in the desired manner, the bar is provided with various keepers and cam surfaces, as clearly indicated in Figs. 5 to 9, inclusive, which will now be explained.

To enable the latch to hold the bar fast in its "A¹" position as indicated in Fig. 6, the bar is provided with an abrupt shoulder 44 adapted to serve as a keeper. So long as the slide-bar 42 is prevented from moving by the permutation mechanism, the bar 27 is held fast by the latch and cannot be moved to its "A²" position or circuit-closing position illustrated in Fig. 5. On setting the permutation mechanism, however, the clearance-ways in the permutation mechanism are brought into registration with the slide-bar 42, after which the bar 27 may be pulled upwardly or to the left, as indicated in Fig. 6, to the circuit-closing position "A²" indicated in Fig. 5, the bar being provided with a knurled head 45 for such purpose. As the bar 27 moves from its "A¹" position to its "A²" position, the latch 28 is caused to swing about the pin 39 until its nose moves clear of the stop 44, after which the latch is caused to return to its normal position by means of a spring 46 (see Figs. 4 and 5), one end of which is secured to a part of the lower framework and the other end to the latch. The movements of the bar 27 from its "A¹" position to its "A²" position and vice versa are limited by stops 47, 48, which make contact with adjacent portions of the upper framework.

On the bar 27, just below the keeper 44, is a cam surface 49 (Fig. 5) by which, as the bar 27 is returned from its "A²" position (Fig. 5) to its "A¹" position (Fig. 6), the latch may be moved rearwardly independently of the condition of the permutation mechanism to a position such as to permit the keeper to be snapped under the latch,

after which the latch may be returned to its normal position by a spring 50 best illustrated in Fig. 4, one end of said spring being connected to the latch and the other end to some appropriate part of the lower framework. 70

When the bar 27 is in its "A²" position (Fig. 5) it may be freely rotated to its "B²" position (Fig. 7), during which rotation the latch will be cammed rearwardly out of the notch adjacent the cam surface 49 until the nose of the latch rests against the adjacent cylindrical portion of the bar. A slight depression of the bar 27 from its "B²" position, that is, a movement towards the right as viewed in Fig. 7, will cause it to be moved to its "B³" position as indicated in Fig. 8. As a means of determining this position, the bar 27 is provided with a notch into which the latch may be moved by the spring 50. 80 The form of this notch is such as to provide an abrupt shoulder 51, adapted to serve as a keeper, and a cam-like surface 52. The keeper 51 cooperates with the latch as a means whereby the return of the bar 27 to its "B²" position (Fig. 7) is prevented except when the permutation mechanism has been set so as to free the slide-bar 42. The cam-like surface 52 provides means whereby the latch may be moved rearwardly to a sufficient distance to free the bar 27 and permit it to be moved to its "B¹" position (Fig. 9). To enable the latch to yieldingly hold the bar in its "B¹" position, the bar is provided with a notch into which the nose of the latch may 100 be moved by the spring 50. The notch is of such form as to provide a cam-like surface 53 by which the latch may be cammed rearwardly to a sufficient distance to permit the bar 27 to be returned from its "B¹" position 105 (Fig. 9) to its "B³" position (Fig. 8).

After setting the permutation mechanism so as to free the slide-bar 42, the bar 27 may be pulled upwardly or to the left from the position indicated in Fig. 8 to its "B²" position indicated in Fig. 7, during which the latch 28 will be swung or rotated slightly about the pin 39 without being released from the keeper 51. While the bar is held in its "B²" position against the effort of the spring 110 46, it may be rotated in a clockwise direction as indicated in Fig. 2 to its "A²" position, during which the nose of the latch will be cammed out of its engaging relation with the keeper 51 and permitted to return to its 115 normal position as indicated in Fig. 5.

The permutation mechanism by which the movements of the slide-bar 42 are controlled is best illustrated by Figs. 10, 11 and 12. This mechanism comprises, in general, a number 120 of permutation wheels each of which has a concealed lock-controlling element and a setting element normally in coupled relationship with its lock-controlling element, a portion of which is accessible for manipulation 130

from the exterior of the casing. In the form in which the mechanism is herein disclosed it comprises four setting elements 54, 55, 56 and 57, normally in coupled relationship with their respective lock-controlling elements 58, 59, 60 and 61, the coupling means being such that the respective elements may be readily uncoupled for a purpose which will herein-after be explained.

- 20 The setting elements 54 to 57, inclusive, are provided with cylindrical surfaces 62 having markings thereon representative of the various positions in which the permutation wheels may be set. In the form herein disclosed, each wheel may be set in ten different positions and the setting elements therefore bear equally-spaced markings comprising a zero and the numerals 1 to 9, as indicated in Fig. 2.
- 20 In order that the markings on the permutation wheels may be observed through windows 63 (Fig. 1) in the casing of limited dimensions so that all of the markings except one on each wheel may be concealed, the 25 wheels are so mounted that the surfaces 62 of the setting elements are slightly back of the surface of the face plate (see Fig. 6).

To facilitate the manipulation of the permutation wheels each of the setting elements 30 is provided with a flange 64 (Figs. 6 and 10) of increased diameter, adapted to project through slots 65 in the face plate, and such flanges may be slightly scalloped or otherwise roughened to provide suitable finger-holds in their exposed edges.

Each of the lock-controlling elements 58 to 61, inclusive, is provided with a cylindrical portion 66 adapted to obstruct movement of portions 67 of the slide-bar 42 except when in one of its ten positions, at which time a slot 68 in the lock-controlling element is moved into registration with the adjacent part 67 of the slide-bar so as to form a clearance-way within which the part 67 may move. 40 In Fig. 10 of the drawing the lock-controlling elements 58 and 60 are represented as having been moved to positions such as would bring their slots 68 in registration with the parts 67 of the slide-bar. The lock-controlling elements 59 and 61 are in such position as to prevent movement of the slide bar. Not until all four of the lock-controlling elements have been moved to the positions indicated in Fig. 12, in which the slot 68 is in registration with the part 67 of the slide-bar, are the parts 67 free to be moved into said slots and permit the movements of the slide-bar and latch upon which certain of the movements of the bar 27 are dependent, as already explained. This movement of the latch which is dependent upon the movement of the elements 67 of the slide-bar into the notches 68 of the lock-controlling elements may be referred to as its "keeper-releasing" movement, and the position to which it is moved

its "keeper-releasing" position, as distinguished from the rearward bar-releasing movement of the latch independently of the movement of the slide-bar.

In order that the position of the slots 68 in the movement-obstructing elements 66 may not be ascertained by pulling the elements 67 into engagement with the movement-obstructing elements and then rotating the permutation wheels so as to discover the positions of the slots by the sense of feeling, each movement-obstructing element 66 is provided with false slots 68' corresponding in number and spacing with the number of positions in which the permutation wheels may be set. Each of these slots conforms in shape with the entrance to the slots 68, so that, while the movement of the slide-bar is prevented by any one of the lock-controlling elements, the sensation which would be produced by rotation of any one of the other lock-controlling elements to each of its ten positions would be identical, thus rendering the discovery of the positions of the slots impossible.

The purpose of making the setting elements of the permutation wheels separate from the lock-controlling elements and providing separable couplings to normally preserve their angular relations is to make it possible to change the combination, as will be hereinafter more fully explained. One satisfactory form of coupling illustrated in Figs. 10 and 11 is effected by providing each of the setting elements 54 to 57, inclusive, with inwardly-directed teeth 69 equal in number to the number of positions in which the permutation wheels may be set, and by providing each of the lock-controlling elements 58 to 61, inclusive, with one or more teeth 70 of which four are used in the form of the invention illustrated in Fig. 11. In order that the lock-controlling elements 58 to 61, inclusive, may be temporarily uncoupled from the setting elements 54 to 57, inclusive, when it is desired to change the combination, the setting elements are so mounted in the casing that movement in an axial direction is prevented, whereas the lock-controlling elements are so mounted that they may be shifted in an axial direction with respect to the setting elements sufficiently to remove the teeth 70 from the teeth 69 and permit the setting elements to be rotated while the lock-controlling elements are held fast. To this end, the four lock-controlling elements 58 to 61, inclusive, are rotatably mounted in end-to-end relation on a pin or shaft 71. Threaded to one end of the pin 71 is a nut 72 having an inwardly-extending portion 73 of reduced diameter adapted to be moved in an axial direction through an opening in a part of the upper framework 21. The opposite end of the shaft 71 is provided with a head 74 adapted to move in an axial direction through another opening in a part of the upper framework 21. Secured to the

120

125

130

end 75 of the shaft 71 which extends beyond the head 74 is a stop member 76 and a manipulator 77, the purpose of which will hereinafter be explained.

5 Subject to the controlling effect of certain stops and movement-obstructing elements hereinafter to be described, the shaft 71, nut 72, head 74, stop member 76, manipulator 77, and lock-controlling elements 58 to 61, inclusive, may be shifted as a unit from the position indicated in Fig. 10 towards the left to a position such that the teeth 70 of each lock-controlling element will be moved out of their meshing relationship with the teeth 69 of the 10 setting elements, so that the latter may be rotated with respect to the former in order to change the combination of the lock.

During the axial movement of the lock-controlling elements axial movement of the setting elements is prevented by the flanges 64 which extend through the slots 65 in the face plate and through slots 78 in the base portion of the upper framework 21. The setting elements are also maintained in a uniformly 20 spaced relation by means of the anti-picking guards 79, 80 and 81, to be hereinafter described. The shaft 71, manipulator 77 and associated parts by means of which the lock-controlling elements may be shifted out of 25 their coupled relation with respect to the setting elements may be referred to as the "coupling disabling device" of the lock.

It will be observed that the anti-picking guards 79, 80 and 81 constitute annular bands 35 arranged in an overlapping or telescoping relation with respect to the setting elements so as to completely enclose the slotted lock-controlling elements. These guards, therefore, make it impossible to discover the relation 40 which exists between the positions of the slots in the lock-controlling elements and the positions of the numerals or other markings on the setting elements by inserting feelers through the windows and slots in the casing 45 at which portions of the setting elements are exposed for purposes of manipulation and observation.

These anti-picking guards are slotted at 50 points 82 farthest removed from the windows 63 and slots 65 in the casing to permit the parts 67 of the slide-bar 42 to enter the slots 68 in the lock-controlling elements. Except for these slots 82 the anti-picking guards are imperforate.

55 In order that the combination may not be changed by anyone other than a person who knows the combination in accordance with which the lock has previously been set, means are provided to prevent the endwise or axial movement of the lock-controlling elements by the coupling disabling device without first setting the permutation wheels in accordance with the old combination. To this end, the anti-picking guard 79 is bent 60 or crimped inwardly at a point just to the

left of its slot 82, as indicated in Fig. 10, to provide a stop 83 (Fig. 12). This stop is so related to the flange on the lock-controlling element 58 which comprises its movement-obstructing element 66 as to prevent axial movement of the lock-controlling element to the left except when its slotted portion 68 is in alignment with the stop 83. When so positioned, the movement-obstructing element may be freely moved to the left, thus causing the parts adjoining the slot 68 to embrace the stop 83 so as to prevent rotation of the lock-controlling element during the rotation of the setting element to change the combination. 70

In like manner, the anti-picking guard 80 is provided with a similar stop 84, which cooperates with the movement-obstructing element 66 of the lock-controlling element 59 to prevent axial movement of said lock-controlling element without first bringing its slot 68 into registration with said stop. 75

In the preferred form of the invention herein disclosed, the position to which the movement-obstructing element 66 of the lock-controlling element 60 is moved to effect a change of the combination is such that no part of the anti-picking guard 80 is available for use as a stop. To provide a stop for this element similar in principle to the stops provided for the lock-controlling elements 58 and 59, the lock-controlling element 60 is grooved circumferentially midway between its ends as at 85, the portion of the lock-controlling element at the right of the groove is provided with a slot 86 in alignment with its slot 68, and the right-hand end of the anti-picking element 80 is bent or crimped inwardly to provide a stop 87 extending somewhat farther inwardly than does its stop 84, so as to cooperate with the slotted portion 86 of the lock-controlling element 60 in the same manner that the stop 83 cooperates with the slotted portion 68 of the lock-controlling element 58. Likewise, the anti-picking guard 81 is provided at its right side with a stop 88 adapted to cooperate in a similar manner with a slot in the right-hand end portion 89 of the lock-controlling element 61. 100

105 It is an object of the invention to provide means whereby the parts of the mechanism may be automatically returned to their normal positions after they have been shifted for the purpose of changing the combination and yet permit the parts to be held in their shifted relationship while the combination is being changed. To this end, a spring 90 is inserted between a portion of the upper framework 21 and the stop 76 on the shaft 71, by which the shaft and all parts connected therewith may be restored to normal positions after a change of the combination has been effected. 110

115 In order that the coupling disabling de- 120

125

vice may be maintained in its shifted position while a change of the combination is being effected, the manipulator 77 (Fig. 10) is extended upwardly through an L shaped slot 91 in the face plate (Fig. 1) so that, when moved to the left to its coupling disabling position, the manipulator may be moved forwardly into a notched portion 92 of the slot 91 and held in that position against the opposing effort of the spring 90. When the change of the combination has been effected, the end of the manipulator 77 may be moved out of the notch 92, after which the spring will return the coupling disabling device and associated parts of the mechanism to their normal positions.

As a further assurance against the disturbance of the combination by anyone other than an authorized person, means is provided to prevent a change of the combination except when the bar 27 has been moved to its released position, that is, either its "A²" position or its "B²" position. To this end, the stop 76 is provided, said stop having a portion 93 (Fig. 2) of a width adapted to move freely between the upper disk 23 and the lower wall of the framework 21, as indicated in Fig. 3, said stop also having a finger 94 so positioned and of such form that it may enter a slot 95 in the bar 27 only when the bar has been moved to its "A²" or "B²" position. When the bar is in any other position, movement of the finger 94 and associated parts to the left is prevented by the portion 96 of the bar 27, as indicated in Figs. 2 and 3.

The stop 76 also cooperates with the bar 27 in such manner as to prevent the movement of the latter from its "A²" or "B²" position to any other position while the coupling disabling device and associated parts are in the positions to which they are shifted when the combination is to be changed. This will be apparent on reference to Fig. 3 in which it will be seen that, when the bar 27 has been moved forwardly to bring the slot 95 in alignment with the finger 94 (see Fig. 7) and the finger 94 moved to the left into its engaging relation with the parts of the bar 27 adjoining the slot 95, the return of the bar 27 to the position indicated in Fig. 3 will be prevented. On moving the coupling disabling device and associated parts including the stop 76 to the right, the finger 94 releases the bar 27, which may then be freely moved subject only to its control by the permutation mechanism.

In order that the manipulator 77 may be rocked sufficiently to permit it to move into and out of the notch 92 (Fig. 1) without also rocking the stop 76 which is intended to have a sliding movement only in the upper framework, the manipulator may be riveted or otherwise permanently secured to the end of the shaft 71, as indicated in Fig. 10, and the extension 75 may be slightly longer than the

thickness of the stop 76 so that the manipulator and shaft may be rocked without rocking the stop.

In the preferred form of the invention, the setting elements of the permutation wheels are mounted in groups, the group at the right side of the mechanism having their setting flanges 64 at the right sides of the setting elements, and the group at the left end of the mechanism having their setting flanges at the left sides of the setting elements. This arrangement is of importance in that it divides the number representing the combination of the lock into a subdivided form more easily read, and positions the setting flanges in groups which may be more conveniently manipulated during the setting operation, especially when setting the device in the dark in a manner to be hereinafter explained. This grouping of the permutation wheels is also of importance in that it disposes the movement-obstructing members of the lock-controlling elements at each end of the mechanism on the side of the setting element nearest the center of the mechanism. This makes it possible to enclose all of the movement-obstructing elements within a series of anti-picking guards extending from setting element to setting element without requiring any guard to be extended from either of the end elements to the adjacent wall of the mechanism. It also makes it possible to use a bolt structure or slide-bar 42 of materially less width than the length of the set of permutation wheels by which it is controlled.

To facilitate the positioning of the respective permutation wheels in each of the ten positions in which they may be set, the setting flange of each setting element may be provided with ten equally-spaced notches 97 (Fig. 6), and spring-detents 98 may be provided so positioned as to be moved into said notches and yieldingly hold the setting elements in any one of their ten positions. In order that it may be possible to set the combination by the sense of feeling alone when illumination is not available, one of the notches 97, as indicated at 99 (Fig. 6), has an abrupt shoulder 100 which prevents rotation of the setting element in one direction. This abrupt shoulder is so positioned as to bring the setting element to rest when rotated in one direction to a position at which its zero appears at the window 63 (Fig. 1). The opposite wall of the notch 99 and both walls of all of the other notches 97 are of gradual inclination so as to provide cam-like surfaces adapted to move the pawl 98 out of the notches on rotation of the permutation wheels.

When setting the combination in the dark, the operator rotates each of the permutation wheels in the direction in which it will be arrested at its zero position by the abrupt shoulder 100. He then rotates each wheel

in the opposite direction through a number of positions dependent upon the combination of the lock. If that combination is 2768, he rotates the first one to its second position, the second one to its seventh position, the third one to its sixth position, and the fourth one to its eighth position. This may be readily effected by the tendency which the permutation wheels will have to hang or linger at each position as the pawl 98 falls in the slot 97. The positions can also be determined by the slight click which takes place as the pawl falls into each notch.

From the foregoing description it will be apparent that the lock embodies several improved features of more or less general application not necessarily dependent upon use in one and the same structure.

The invention may be applied to any device having a bolt or bar which may at times be conditioned for movement from an effective to an ineffective position, in one of which it may be locked and from which it may be released only after setting a permutation mechanism in accordance with a predetermined combination. At other times the bolt or bar may be conditioned for movement at will from an effective to an ineffective position, and its change from such condition to the first described condition made dependent upon a setting of the permutation mechanism. When, as herein disclosed, the invention is applied to a motor vehicle switch lock, it may be operated in the following manner: Starting with the switch-controlling bar 27 locked in its open circuit position "A¹", the driver on entering the car may close the ignition circuit by setting the permutation mechanism in accordance with the combination of the lock, after which the bar may be withdrawn to its circuit-closing position "A²". In order that the driver may not forget to lock the switch on leaving the car, he may immediately disturb the position of one or more of the permutation wheels, thereby at the same time concealing the combination. When the driver desires to leave the car, he opens the switch by pressing the bar to its "A¹" position in which it is immediately held fast by the latch.

If, after the driver has unlocked the switch bar and moved it to its circuit-closing position "A²", he desires to turn the car over to an attendant at a garage who will have occasion to move the car from place to place, the driver, instead of locking the switch by moving it to its position "A¹", rotates the bar to its position "B²" and presses it inwardly to either its "B³" or "B⁴" position. When thus conditioned, the attendant at the garage may open and close the ignition circuit at will by moving the bar from its "B³" position to its "B⁴" position, or vice versa, but he will be unable to discover the combination of the lock the wheels of which were dis-

turbed by the driver before turning the car over to the attendant, and the switch bar cannot be restored to its normal condition so as to be accidentally locked by movement of the bar from its "A²" position to its "A¹" position without again setting the permutation mechanism in accordance with the combination of the lock. When the car is returned to the owner or driver who knows the combination, the lock may be restored to its normal condition by first setting the permutation mechanism, then drawing the bolt from its "B³" position to its "B²" position and rotating it to its "A²" position. One or more wheels of the permutation wheels should then be again disturbed so as to conceal the combination and the lock is in readiness for normal use. It may again be locked by pressing the bar to its "A¹" position or may be conditioned for placing in the garage by rotation to its "B²" position and movement to its "B¹" position.

As already explained, the combination may be changed, when desired, by first setting the permutation mechanism in accordance with the combination previously used, then pressing the manipulator 77 (Fig. 1) to the left and moving it downwardly into the notch 92. The setting elements may then be rotated to positions corresponding with the desired new combination while the lock-controlling elements are held fast by the stops 83, 84, 87 and 88. This movement of the manipulator 77 to its combination-changing position can only be effected when the switch-operating bar 27 has been moved to its "A²" or "B²" position, and after the manipulator of the coupling disabling device has been moved to its combination-changing position the switch-operating bar cannot be moved out of its "A²" or "B²" position without first returning the manipulator 77 and connected parts to their normal positions.

The invention is not intended to be limited to the specific form herein disclosed for purposes of illustration but should be regarded as covering modifications and variations thereof within the scope of the appended claims.

What I claim is:

1. A lock comprising a mounting member, a bar swiveled in said member so as to be rotatable from an angular position "A" to an angular position "B", and vice versa, the bar being movable endwise when in either of said angular positions from a longitudinal position "1" to a longitudinal position "2", and vice versa, movement-obstructing means preventing rotational movement of the bar except when in position "2", a latch by which the bar may be engaged and held fast in its "A¹" position, and a permutation mechanism by which the release of the bar from the latch may be conditioned on the

setting of the mechanism in accordance with a predetermined combination.

2. A lock, as defined by claim 1, having a latch-engaging keeper on its bar as the means by which the latch may hold the bar fast in its "A¹" position, and movement-obstructing portions on the latch and parts of the permutation mechanism whereby the movement of the latch to a keeper-releasing position may be conditioned upon the setting of the mechanism in accordance with a predetermined combination, the bar being movable from its "A¹" position to its "A²" position when the mechanism is so set.

3. A lock, as defined by claim 1, having a cam-like latch-engaging element on its bar to serve as a means whereby the latch may yieldingly hold the bar in its "A²" position, the latch being movable, by the cam-like element, irrespective of the condition of the permutation mechanism, to a bar-releasing position, thereby permitting the bar to be moved to its "A¹" position or to its "B²" position, the latch having resilient means tending to hold it in its normal bar-engaging relationship and to return it thereto when removed therefrom.

4. A lock, as defined by claim 1, having a latch-engaging keeper on its bar as the means by which the latch may hold the bar fast in its "A¹" position, a cam-like latch-engaging element on its bar whereby the latch may yieldingly hold the bar in its "A²" position, and movement-obstructing portions on the latch and parts of the permutation mechanism whereby the movement of the latch to a keeper-releasing position, to permit the bar to be moved from its "A¹" position to its "A²" position, may be conditioned upon the setting of the mechanism in accordance with a predetermined combination, the latch being movable, by the cam-like element, irrespective of the condition of the permutation mechanism, to a bar-releasing position, other than its keeper-releasing position, such as will permit the bar to be moved from its "A²" position to its "A¹" position or from its "A²" position to its "B²" position, resilient means being provided tending to hold the latch in its normal bar-engaging relationship and to return it thereto when removed therefrom.

5. A lock, as defined by claim 1, having a cam-like latch-engaging element on its bar to serve as a means whereby the latch may yieldingly hold the bar in a position "B³" intermediate its "B¹" and "B²" positions, the latch being movable, by the cam-like element, irrespective of the condition of the permutation mechanism, to a bar-releasing position such as to permit the bar to be moved from its "B³" position to its "B¹" position.

6. A lock, as defined by claim 1, having a

cam-like latch-engaging element on its bar to serve as a means whereby the latch may yieldingly hold the bar in its "B¹" position, the latch being movable, by the cam-like element, irrespective of the condition of the permutation mechanism, to a bar-releasing position, thereby permitting the bar to be moved from its "B¹" position to a position "B³" intermediate its "B¹" and "B²" positions.

7. A lock, as defined by claim 1, having spaced cam-like latch-engaging elements on its bar to serve as means whereby the latch may yieldingly hold the bar either in its "B¹" position or in a "B³" position intermediate its "B¹" position and its "B²" position, the latch being movable, by the cam-like elements, irrespective of the condition of the permutation mechanism, to a bar-releasing position such as to permit the bar to be moved from its "B¹" position to its "B³" position, or vice versa, the latch having resilient means tending to hold it in its normal bar-engaging relationship and to return it thereto when removed therefrom.

8. A lock, as defined by claim 1, having a latch-engaging keeper on its bar as the means by which the latch may hold the bar fast in its "A¹" position, cam-like latch-engaging elements on the bar whereby the latch may yieldingly hold the bar either in its "A²" position, or in its "B¹" position, or in a "B³" position intermediate its "B¹" position and its "B²" position, a latch-engaging keeper on its bar whereby the latch may prevent movement of the bar from its "B³" position to its "B²" position, movement-obstructing portions on the latch and parts of the permutation mechanism whereby the movement of the latch to a keeper-releasing position, to permit the bar to be moved from its "A¹" position to its "A²" position, or from its "B³" position to its "B²" position, may be conditioned upon the setting of the mechanism in accordance with a predetermined combination, the latch being movable, by the cam-like elements, irrespective of the condition of the permutation mechanism, to a bar-releasing position, other than its keeper-releasing position, such as will permit the bar to be moved from its "A²" position to its "A¹" position, or from its "A²" position to its "B²" position and thence to its "B³" position, or from its "B³" position to its "B¹" position, or vice versa, independently of the setting of the permutation mechanism, resilient means being provided tending to hold the latch in its normal bar-engaging relationship and to return it thereto when removed therefrom.

9. A lock comprising a mounting member, a bar swiveled in said member so as to be rotatable from an angular position "A" to an angular position "B", and vice versa, the bar being movable endwise when in either of said

angular positions from a longitudinal position "1" to a longitudinal position "2", and vice versa, movement-obstructing means preventing rotational movement of the bar except when in position "2", a latch by which the bar may be yieldingly held in a position "B³" intermediate its "B¹" and "B²" positions, and a permutation mechanism by which the movement of the bar from its "B³" position to its "B²" position may be conditioned on the setting of the mechanism in accordance with a predetermined combination.

10. A lock, as defined by claim 9, having a cam-like latch-engaging element on its bar 15 to serve as a means whereby the latch may yieldingly hold the bar in its "B¹" position, the latch being movable, by said cam-like element, irrespective of the condition of the permutation mechanism, to a bar-releasing position such as to permit the bar to be moved from its "B¹" position to its "B³" position.

11. A lock, as defined by claim 9, having a cam-like latch-engaging element on its bar whereby the latch may yieldingly hold the bar in its "B³" position, a latch-engaging keeper on its bar as the means by which the latch may prevent movement of the bar from its "B³" position to its "B²" position, and movement-obstructing portions on the latch and parts of the permutation mechanism whereby the movement of the latch to a keeper-releasing position, to permit the bar to be moved from its "B³" position to its "B²" position, may be conditioned on a setting of 35 the mechanism in accordance with a predetermined combination, the latch being movable, by the cam-like element, irrespective of the condition of the permutation mechanism, to a bar-releasing position, other than its keeper-releasing position, such as will permit the bar to be moved from its "B³" position to its "B¹" position.

12. A lock, as defined by claim 9, having latch-engaging keepers on its bar by which 45 the latch may hold the bar fast in its "A¹" position, or may prevent movement from its "B³" position to its "B²" position, and movement-obstructing portions on the latch and parts of the permutation mechanism whereby the movement of the latch to a keeper-releasing position may be conditioned upon the setting of the mechanism in accordance with a predetermined combination, the bar being movable from either its "A¹" position to its 50 "A²" position or from its "B³" position to its "B²" position when the mechanism is so set.

13. A lock, as defined by claim 9, having a cam-like latch-engaging element on its bar to 60 serve as a means whereby the latch may yieldingly hold the bar in its "A²" position, the latch being movable, by said cam-like element, irrespective of the condition of the permutation mechanism, to a bar-releasing po-

sition, thereby permitting the bar to be moved to its "A¹" position.

14. A lock comprising a mounting member, a bar mounted for movement with respect thereto from a "locked" position to a "released" position, and vice versa, a spring latch, a keeper on the bar into engaging relation with which the latch may be snapped when the bar is moved from its "released" position to its "locked" position, a cam-like element on the bar by which the latch may yieldingly hold the bar in its "released" position, and a permutation mechanism by which the movement of the latch to a keeper-releasing position may be conditioned on the setting of the mechanism in accordance with a predetermined combination, the bar being movable from its "locked" position to its "released" position when the mechanism is so set, the latch being movable by the cam-like element, irrespective of the condition of the permutation mechanism, to a bar-releasing position, other than its keeper-releasing position, such as to permit the bar to be moved from its "released" position to its "locked" position, resilient means being provided to hold the latch in its normal bar-engaging relationship and to return it thereto when released by said keeper or by said cam-like element.

15. A permutation mechanism for a lock comprising tumblers, each having a lock-controlling element, a setting element therefor, and a coupling means normally preventing angular movement of one with respect to the other, a coupling disabling device by which the elements of the tumblers may be uncoupled to permit the combination of the mechanism to be changed, motive means normally holding the disabling device in its normal ineffective position and tending to return it thereto when moved therefrom, and a stop into engagement with which said disabling device may be moved when in its effective position and held against the opposing effort of said motive means while a change of the combination is being effected.

16. A permutation lock comprising a mounting member, a bar movable with respect thereto from a "locked" position to a "released" position, and vice versa, a permutation mechanism by which the movement of the bar from its "locked" position to its "released" position may be conditioned on the setting of the mechanism in accordance with a predetermined combination, said permutation mechanism comprising tumblers each having a lock-controlling element, a setting element therefor, and coupling means normally preventing angular movement of one with respect to the other, a coupling disabling device by which the elements of the tumblers may be uncoupled to permit the combination of the lock to be changed, and movement-obstructing elements on said bar

and disabling device to prevent an uncoupling movement of the latter without first moving the former to its "released" position.

17. A permutation lock comprising a mounting member, a bar movable with respect thereto from a "locked" position to a "released" position, and vice versa, a permutation mechanism by which the movement of the bar from its "locked" position to its "released" position may be conditioned on the setting of the mechanism in accordance with a predetermined combination, said permutation mechanism comprising tumblers each having a lock-controlling element, a setting element therefor, and coupling means normally preventing angular movement of one with respect to the other, a coupling disabling device by which the elements of the tumblers may be uncoupled to permit the combination of the lock to be changed, and movement-obstructing parts on said bar and disabling device to prevent the movement of the former from its "released" position to its "locked" position while the latter is in its coupling disabling position.

18. A permutation lock comprising a mounting member, a bar movable with respect thereto from a "locked" position to a "released" position, and vice versa, a permutation mechanism by which the movement of the bar from its "locked" position to its "released" position may be conditioned on the setting of the mechanism in accordance with a predetermined combination, said permutation mechanism comprising tumblers each having a lock-controlling element, a setting element therefor, and coupling means normally preventing angular movement of one with respect to the other, a coupling disabling device by which the elements of the tumblers may be uncoupled to permit the combination of the lock to be changed, movement-obstructing elements on said bar and disabling device to prevent an uncoupling movement of the latter without first moving the former to its "released" position, and movement-obstructing parts on said bar and disabling device to prevent the movement of the former from its "released" position to its "locked" position while the latter is in its coupling disabling position.

19. A lock comprising a mounting member, a bar movable therein from a "locked" position to a "released" position, and vice versa, a keeper and a cam surface on said bar, a latch movable into an engaging relation with said keeper, said latch being movable to a keeper-releasing position on movement of said bar from its "locked" position to its "released" position, a permutation mechanism by which such movement of the latch and bar may be conditioned on the setting of the mechanism in accordance with a predetermined combination, said latch being movable by said cam surface, independently

of the condition of said permutation mechanism, to a bar-releasing position other than said keeper-releasing position, on movement of said bar from its "released" position to its "locked" position, and resilient means for moving said latch into engaging relation with said cam surface when released from said keeper on movement of said bar from its "locked" position to its "released" position, and for moving said latch into engaging relation with said keeper when released from said cam surface on movement of said bar from its "released" position to its "locked" position.

20. A permutation lock mechanism comprising a series of permutation wheels each having a setting element and a lock-controlling element having a clearance-way therein to receive a portion of a bolt when set, the wheels at each end of the series having their lock-controlling elements between their respective setting elements and the setting elements of the adjoining wheels of the series, thus necessitating the location of the lock-controlling elements of two wheels of the series adjacent each other between their respective setting elements.

21. A permutation lock mechanism, as defined by claim 20, said mechanism being mounted in a casing with its setting elements exposed for manipulation through windows in one of its walls, and a series of anti-picking guards disposed between the lock-controlling elements and the windows in said casings, said guards extending from setting element to setting element throughout the series of permutation wheels.

22. A permutation lock mechanism, as defined by claim 20, said mechanism being mounted in a casing with its setting elements exposed for manipulation through windows in one of its walls, and a series of anti-picking guards comprising cylinders in telescopic relation with the setting elements of said permutation wheels and extending from wheel to wheel throughout the series, said guards having openings therein at points directed away from the windows in said casing to permit parts of a bolt to be extended into cooperative relation with the lock-controlling elements, said guards being otherwise imperforate.

23. A lock comprising a mounting member, a bar movable therein from a "free" position to a "controlled" position, and vice versa, a permutation lock mechanism to control movements of said bar, and movement-obstructing means cooperating with said mechanism to prevent the movement of said bar from its "free" position to its "controlled" position except when said mechanism has been set in accordance with a predetermined combination, said bar being movable from an "effective" to an "ineffective" position,

and vice versa, when in either its "free" or its "controlled" position.

24. A lock, as defined by claim 23, having a cooperating connecting means between its bar and its permutation lock mechanism whereby the bar may be yieldingly held in one of its "controlled" positions, from which it may be moved to the other, irrespective of the condition of the permutation mechanism, said connecting means being such that the return of said bar may be conditioned upon the setting of said mechanism in accordance with a predetermined combination.

25. A lock, as defined by claim 23, having a cooperating connecting means between its bar and its permutation lock mechanism whereby the bar may be yieldingly held in either of its "free" positions and moved to the other, irrespective of the condition of the mechanism.

26. A lock comprising a mounting member, a bar movable therein from a "free" position to a "controlled" position, and vice versa, said bar being movable from an "effective" position to an "ineffective" position, and vice versa, when in either its "free" position or its "controlled" position, a permutation lock mechanism to control movements of said bar, and connecting means between said mechanism and said bar whereby the latter may be yieldingly held in one of its "controlled" positions from which it may be moved to its "free" position or to the other of its "controlled" positions, irrespective of the condition of the mechanism, said connecting means being such that the return of said bar from the last-mentioned position may be conditioned on the setting of the mechanism in accordance with a predetermined combination.

27. A permutation lock comprising a mounting member and a bar movably mounted therein so that it may be shifted from one to the other of two positions from each of which it may be displaced by a movement other than its shifting movement to a new position, movement-obstructing means on said bar and mounting member whereby the shifting movement of the bar is prevented when it has been moved in the second-mentioned sense away from either of the two first-mentioned positions, and means including a permutation lock mechanism whereby various movements of said bar with respect to said mounting member may be controlled.

28. A permutation lock comprising a mounting member, a series of permutation wheels rotatably mounted therein and each comprising a setting element and a lock-controlling element, the wheels at each end of the series having their lock-controlling elements between their respective setting elements and the adjacent wheels, thus necessitating the location of the lock-controlling elements of two wheels of the series adjacent

each other between their respective setting elements, a bolt slidably mounted in said mounting member for movement in a direction perpendicular with respect to the axis of the series of permutation wheels, and movement-obstructing elements on said bolt and lock-controlling elements preventing a releasing movement of the bolt except when said permutation wheels are set in a predetermined relation, the arrangement of bolt and permutation wheels thus defined being such that the width of the bolt may be less than the distance between the setting elements of the two end wheels.

29. A permutation lock comprising a casing having windows and slots therein, the slots extending beyond the ends of the windows, a permutation mechanism mounted therein having dial wheels each comprising a cylindrical indicia-bearing element and a concentric circular setting flange of increased diameter at one side of said indicia-bearing element, each of said wheels being mounted in said casing with a portion of its indicia-bearing surface exposed at one of said windows, and a portion of its setting flange extended through one of said slots so as to be accessible for manipulation, the indicia-bearing elements and setting flanges and their respective windows and slots being differentiated by making them "right and left", a right dial having its setting flange at the right of its indicia-bearing element, and a left dial having its setting flange at the left of its indicia-bearing element, the windows and slots being correspondingly positioned.

In witness whereof, I have hereunto signed my name.

ALEXANDER G. HATCH.
